UNITED STATES PATENT OFFICE.

DAVID GIBBONS, OF JOPPA, INDIANA, ASSIGNOR OF TWO-THIRDS TO
ALBERT HAGEE AND EDMUND THOMPSON, BOTH OF SAME PLACE.

WEATHER-STRIP.

SPECIFICATION forming part of Letters Patent No. 296,158, dated April 1, 1884.

Application filed December 15, 1883. (No model.)

To all whom it may concern:

Be it known that I, DAVID GIBBONS, a citizen of the United States, residing at Joppa, in the county of Hendricks and State of Indiana, have invented certain new and useful Improvements in Weather-Strips; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of a vertical section of a portion of a door and sill, showing my improvements applied. Fig. 2 is a horizontal sectional view of the same, showing the door partly open; and Fig. 3 is a vertical sectional view of the sill, showing my invention applied to a door.

This invention has relation to weather-strips for doors; and it consists in the construction and novel arrangement of simple devices whereby an effective protection to the opening between the door and sill is provided in an inexpensive manner.

In the accompanying drawings, the letter A designates the door, and B the door-sill or threshold-strip in the doorway. This strip is provided with an extension or bearing, C, on the inside of the doorway, near its hinged portion. The surface of this extension is level with the top of the threshold-strip, with which it is continuous. Usually the threshold-strip and its extension are covered with tin or zinc.

D represents the weather-strip, which is made of sheet metal, and consists of two portions—the upper or stationary part, E, which is secured to the door, and its lower movable part or guard-plate, F, which is connected to the upper portion by a longitudinal joint, as at G. This joint is formed in the following manner: The upper or stationary portion, E, of the strip is made vertical in its upper part, h, and this vertical flange is perforated for the passage of the tacks or screws, whereby it is secured to the door. From this vertical flange the body of this piece E extends out-

ward and downward obliquely, as shown at k, 50 and the lower marginal portion of the piece is turned inward in the form of a long horizontal under-hook flange, z, the edge of which, while it approaches the surface of the door, does not touch it, an interval being left for 55 the play of the upper part of the movable lower portion, F, of the strip, the upper marginal portion of which is bent outward, forming an over-hook flange, m, which engages the inwardly turned or reversed flange z of the 60 upper piece. The lower section, F, is prevented from any lateral displacement of the upper section by means of pins i i, which are driven in the door at the respective ends of the joint G. In this manner a strong horizontal 65 joint is formed, which is without perforation or opening in either flange. The lower portion of the movable piece F is bent in outward concave form, as shown, so that it will move easily and without noise over the carpet and 70 threshold. When the horizontal hook-joint is properly formed, the hook-flanges are so arranged that they provide, by their engagement, a stop preventing the movable piece from swinging below a certain level, so that 75 it need not touch the carpet. When the door is closed, the guard-plate of the strip is raised automatically and gradually by the salient portions of the extension, so that it passes over the threshold easily and without noise. With 80 this strip no molding of wood is required, and a spring is unnecessary.

I am aware that it is not new to construct a weather-strip in two sections, the adjacent horizontal ends of which are bent in opposite 85 directions for engagement with each other, and that door-sills have been provided on their inner sides with a semicircular extension for guiding the lower section of the strip to its proper position, and therefore do not claim 90 such constructions, broadly; but,

Having described this invention, what I claim, and desire to secure by Letters Patent, is—

The combination, with the door-sill having 95 the metal facing, and provided with the extension C on the inner side thereof, near the hinged side of the door, of the door and weath-

er-strip consisting of the upper section having the straight portion *h*, the oblique portion *k*, and the inward hook *z*, and the lower section having the upper outward hook, *m*, and 5 the lower outwardly-concave portion, *F*, the said lower section being prevented from lateral displacement with the upper hooked section by means of the pins *i i*, which are driven

in the door at the respective ends of the strip-hinge, substantially as set forth. 10

In testimony whereof I affix my signature in presence of two witnesses.

DAVID GIBBONS.
